UNITED STATES PATENT OFFICE.

WILLIAM F. RICE, OF PLUM CREEK, NEBRASKA.

DOUBLE LOOP AND BUCKLE FOR HARNESS-SADDLES.

SPECIFICATION forming part of Letters Patent No. 372,331, dated November 1, 1887.

Application filed March 14, 1887. Serial No. 230,858. (No model.)

To all whom it may concern:

Be it known that I, WILLIAM F. RICE, a citizen of the United States of America, and a resident of Plum Creek, in the county of Dawson and State of Nebraska, have invented an Improved Double Loop and Buckle for Harness-Saddles, of which the following is a specification.

My invention relates to the manner of combining the girths or traces with the skirt-piece of the saddle without sewing; and my invention consists in the construction and combination of a double metal loop and buckle, single metal loops having flat and perforated bases, and leather straps, as hereinafter set forth, pointed out in my claims, and illustrated in the accompanying drawings, in which—

Figure 1 is a top view of my double loop and buckle. Fig. 2 is a top view of my single loop; Fig. 3, a top view of a section of a harness-saddle having a girth detachably connected therewith by means of my invention, and Fig. 4 a longitudinal section of Fig. 3. Fig. 5 is a top view of a metal hook and loops combined. Fig. 6 shows the same applied.

a is the flat base of my double loop. It has an elongated opening in the center of the base and a cross-bar, *b*, in said opening.

c is a tongue hinged to the cross-bar. *d d* are perforations through which rivets are passed to secure the complete device to the leather skirt-piece of a harness-saddle, as shown in Figs. 3 and 4.

g g are loops formed integral with the base *a* to project upward and in opposite directions.

h is a single loop having an integral and perforated flat base, *m*, adapting it to be riveted to a strap, as shown in Figs. 3 and 4.

h' is a modified form of single loop in which the top portion of the loop is in two parts, as required, to widen the top of the loop without increasing its weight.

f is the skirt-piece of a harness saddle, to which the double loop and buckle and a leather strap, *r'*, are jointly riveted.

r'' is a second leather strap placed under the strap *r'*, and the two straps and the single loop *h* then jointly riveted to the lower end 50 of the skirt-piece *f* in such a manner that the two straps *r'* and *r''* can be jointly passed through a ring on the end of a girth and then doubled and passed under the loop *r* and buckled fast in the double loop and buckle, as 55 clearly shown in Figs. 3 and 4. The single loop *h* is riveted to the skirt-piece above the buckle in such a manner that the ends of the straps *r'* and *r''* can be tucked under it and retained flat under the skirt-piece. 60

s is the flat and perforated end of a hook that has integral loops *s'*, on its opposite sides. It is adapted to be applied in place of the strap *r''* and loop *h*, as shown in Fig. 6. The metal hook thus attached will admit the ring on the 65 end of a girth and prevent the wear of the leather strap *r'*.

I am aware that a double loop and buckle has been made by attaching a tongue to a plate and then combining the plate and tongue 70 with a base-plate having loops at its ends; but my manner of forming an integral bar in the center of a base having loops at its ends and hinging a tongue direct to said bar and plate is novel and advantageous. 75

I claim as my invention—

1. A double metal loop and buckle comprising a flat and perforated base, *a*, having a cross-bar, *b*, a tongue, *c*, and loops *g g*, substantially as shown and described, for the purposes stated. 80

2. The combination of the metal double loops and buckle *a b c d* herein described, the single loops *h* and *h'*, and the leather straps *r'* and *r''*, with the leather skirt-piece *r*, of a 85 harness-saddle, substantially as shown and described, for the purposes stated.

WILLIAM F. RICE.
